UNITED STATES PATENT OFFICE.

WILLIAM W. BATCHELDER, OF NEW YORK, N. Y.

CIGAR-LIGHTER.

SPECIFICATION forming part of Letters Patent No. 241,781, dated May 24, 1881.

Application filed March 8, 1881. (No model.)

To all whom it may concern:

Be it known that I, WILLIAM W. BATCHELDER, of the city, county, and State of New York, have invented a new and Improved Cigar-Lighter; and I do hereby declare that the following is a full, clear, and exact description of the same, reference being had to the accompanying drawings, forming part of this specification, in which—

10 Figure 1 is a side view; Fig. 2, a longitudinal section; Fig. 3, a transverse section through the line xx . Fig. 4 is a detail view of the tube for feeding the fibrous cord.

15 My invention relates to an improved cigar-lighter designed to be carried in the pocket and adapted to light a cigar in the open air or anywhere else without regard to the wind.

20 I have heretofore patented a cigar-lighter in which the lighting of a fibrous cord or slow match was effected by the union of two kinds of composition placed in sticks side by side, which would not explode or burn when separated in bulk, but when scraped together and mixed to form a pulverulent charge would explode by friction. I refer particularly to my 25 Patent No. 204,284.

My present invention is an improvement upon this device; and it consists in a simplified structure, in which the two igniting compositions are embodied in longitudinal sections 30 in one stick to form a single continuous match, as more fully described in another application which I have made for the same. In connection with this I provide special carrying and 35 working devices for operating the igniting match and the fibrous slow match, as will be hereinafter more fully described.

Before entering upon a description of the peculiarities of this device I would state that 40 I employ herein the same continuous match which I have filed an application for of even date herewith, and in which the different compositions are molded or formed together in one stick or pencil. I also follow the same general movement for scraping up and mixing the several ingredients of the match which is described in a second pending application of even date, entitled a "gas-lighting device," and which I will refer to again hereinafter.

45 In the drawings, A represents a tube, in which is screwed by a short thread, t , another tube,

B, carrying a fibrous slow match, C. This tube B has rigidly attached to its inner periphery a spiral wire, a , soldered to the tube, and through the center of which spiral the fibrous cord is fed by being turned on its center, the spiral serving the purpose of a feeding-screw to feed the cord up as it is burned away and withdraw it when it is to be extinguished. The end of tube A has a swivel-connection with another tube, D, which latter forms a chamber that contains the continuous lighting-match E. The end of tube A next to the match E is also cut away on both sides, as shown in Fig. 1, so that the end of the slow match in tube 55 B may have a sufficient access of air to burn, the tube B having, by reason of its screw-thread, however, a range of movement past the cut-away parts, so as to be closed against the part e to completely smother the fire on the slow 60 match when it is to be put out after being used.

Within the part e of tube A is arranged the drill-point d , which latter is arranged diametrically across the tube, and is formed (as described in my pending application for a gas-lighting device) with its edges tapered to a point toward the igniting-match E, and its point in line with the longitudinal center of said match, and formed with reverse bevels on opposite sides of said center, so that when the 80 match E is turned about its axis in one direction the drill-point d cuts up and mixes the materials of the continuous match, and when turned in the opposite direction rubs and ignites the mixed pulverulent charge. This general movement for scraping, mixing, and igniting the charge is the same as that which is covered in my said application for a gas-lighting device.

For carrying the match E and feeding it up 90 against the cutting-edge the tube D is slotted lengthwise and a ring, f , placed around the tube and connected through this slot with a friction-cup, e , that contains one end of the match, which ring f is prevented from slipping 95 off at the end by a cap-piece, g .

Now, for operating the cigar-lighter as thus described, the tube D is turned through its swivel-connection over the tube A and the match E forced at same time upwardly against 100 the cutting-point by the pressure of the fingers on ring f . For a movement of the match in one

direction over the drill-point the materials of the match are scraped up and mixed, while the reverse movement rubs and ignites the charge.

With respect to that part of my invention for feeding the fibrous match up in tube B, I would state that I have shown and described in a prior patent, No. 222,649, a spiral wire loose in a tube, and attached to a cap-piece which was swiveled, and when turned axially 10 turned the spiral wire and fed the fibrous match through. This I find does not work, and my improvement of that feature consists in rigidly fastening the spiral to or forming it on the interior of the tube and then causing the fibrous 15 cord to be fed through the same by a turn of the fibrous cord itself. This is a great deal cheaper and simpler, is not liable to get jammed or out of order, and works perfectly.

Having thus described my invention, what 20 I claim as new is—

1. A cigar-lighter composed of a tube for holding the fibrous cord, another tube arranged in line with the same and containing the continuous match, and means for cutting and exploding the charge from the continuous match, substantially as described. 25

2. In a cigar-lighter, the combination of a fibrous cord and a feeding-tube having a spiral wire rigidly fixed in said tube for feeding the cord through by turning the latter, as described. 30

3. The tubes A and D, swiveled together and provided with a cutting-edge between them for the continuous match, combined with a tube carrying the fibrous cord and entered into tube A, and a holder for the continuous match contained in tube D, substantially as and for the purpose described. 35

4. The tube A, having its end cut away, as shown, combined with the lighting device, as described, and a tube carrying the fibrous cord, 40 which latter tube has a range of adjustment past the cut-away portions of tube A, as described.

5. The combination of slotted tube D, the cup e, and ring f, carrying the match E, and the tube 45 A, having a swivel-connection with D and carrying the cutting devices, as described.

W. W. BATCHELDER.
